TOY SEAL

Charles K. Grieder, 700 S. Lyon,
Santa Ana, Calif. 92705

Filed Nov. 15, 1971, Ser. No. 199,092

Term of patent 14 years

Int. Cl. D21—01

U.S. Cl. D34—15 B

FIG. 1 is a side elevational view of a toy seal showing my present design;

FIG. 2 is a front elevational view thereof;

FIG. 3 is a top plan view of such toy;

FIG. 4 is a bottom plan view of the toy showing my design; and

FIG. 5 is a rear elevational view of such toy having my design.

I claim:

The ornamental design for a toy seal, substantially as shown and described.
